UNITED STATES PATENT OFFICE.

CHALMERS K. BRYCE, OF CRANFORD, NEW JERSEY, ASSIGNOR TO OXWELD ACETYLENE COMPANY, OF CHICAGO, ILLINOIS, A CORPORATION OF WEST VIRGINIA.

BAR-CUTTING APPARATUS.

1,260,316.

Specification of Letters Patent. Patented Mar. 26, 1918.

Application filed August 18, 1916. Serial No. 115,142.

To all whom it may concern:

Be it known that I, CHALMERS K. BRYCE, a citizen of the United States, residing at Cranford, county of Union, and State of New Jersey, have invented certain new and useful Improvements in Bar-Cutting Apparatus, of which the following is a full, clear, and exact description.

This invention relates to devices for cutting metal bars, particularly bars and the like of large diameter, by means of an oxy-acetylene or similar blowpipe or "torch," and its chief object is to provide a semi-automatic apparatus for making a clean narrow cut in a simple and expeditious manner. To this and other ends the invention consists in the novel features and combinations hereinafter described.

One form of the invention is illustrated in the accompanying drawings, in which—

Figure 1 shows the apparatus in front elevation, with a round bar in place ready to be cut.

Fig. 2 is a rear elevation.

Fig. 3 is a detail, view showing the rack and pinion provided for raising and lowering the blowpipe.

The operative parts of the apparatus illustrated are mounted on a support 10 of the general form of an inverted V which is adapted to straddle or be set down over the work, the latter being the round bar 11. The V shape of the support 10 is an advantageous feature, as it not only permits the apparatus to be used on bars of widely different diameters but also insures that the axes of such bars will always be in the line bisecting the V. Pivoted to one of the legs of a transverse clamping member 12 and on the other leg is a depending link or shackle 13 adapted to engage and secure the free end of the member 12 as shown. A set-screw 14 threaded in the center of the clamping member serves to bind the entire device firmly on the bar 11.

The blowpipe 15, with its nozzle down, is vertically movable in a sleeve or carrier 16, the lower end of which is split and provided with a binding bolt 17 so that the blowpipe can be tightly fixed in any desired position. A longitudinal rack 18 on the blowpipe, extending through a slot 19 in the carrier, cooperates with a pinion 20 journaled on the carrier and provided with a finger button 21,

so that the blowpipe can be accurately adjusted up or down with respect to the work 55 11. At the upper end of the blowpipe are the usual nipples 22, 23, and regulating valves 24, 25, for connection by means of flexible tubing (not shown) with a source of oxygen and a source of combustible gas, as acetylene or hydrogen.

The sleeve or blowpipe carrier 16 is pivotally mounted on two arms 26, 27, which at their other ends are pivoted on "parallel" 65 centers 28, 29; the distance between these centers being exactly the same as that between the centers by which the arms are connected to the carrier. Also, the two centers are in the line bisecting the angle of 70 this support. In other words, they are in line with the axis of the bar 11. Hence the blowpipe is maintained in constant parallelism with its successive positions and with the said bisecting line as the arms swing upwardly and downwardly to carry the nozzle across the work. The cutting must thus proceed straight across the bar, the flame continually meeting uncut metal instead of being sometimes projected into a space where 80 a cut has already been made, as so often happens when the torch is guided entirely by hand.

The two arms, 26, 27, are slotted longitudinally so that the carrier 16 can be adjusted toward or from the centers 28, 29, on the upward extension 10^a of the V-shaped casting 10, thus accommodating the machine to work on bars of different diameters. The adjustable connection between the carrier and said arms may be of any suitable kind. In the construction shown, the two spindles 30, projecting laterally from the carrier, are provided with sleeves or bushings 31 which pass through the slots in the 90 arms and are capable of turning smoothly on the spindles. These sleeves may be flattened outside to prevent them from turning in said slots. Binding nuts 32, threaded on the outer ends of the sleeves or bushings, 100 serve to clamp the sleeves and arms tightly together after the desired adjustment of the carrier toward or from centers 28, 29, has been made. The nuts 33 on the spindles 30 permit sufficient loosening of nuts 32 for adjustment purposes, without allowing the same to be carelessly taken off and lost. The shafts 28, 29, on which the swinging

arms 26, 27, are pinned, extend through to the back of the V-shaped casting or support, and on their rear ends are pinned two shorter arms 35, 36, of equal length, connected by a link 37. This link is not essential, but it is convenient, since, being of the same length as the distance between the shafts 28, 29, it insures constant parallelism of the arms 26, 27 and hence facilitates adjustment of the blowpipe carrier toward and from said shafts. Fixed on the lower shaft, 29, is a worm gear 38, meshing with a worm 39 pinned to the transverse shaft 40 which is journaled in bosses 41 on the support 10. A hand-wheel or crank disk 42 is fixed on the support end of the shaft. Rotation of the shaft, by the handwheel or by a suitable motor (not shown) then swings the arms 26, 27, and carries the blowpipe 20 slowly across the bar 11. The use of speed-reducing gearing between the handwheel and the swinging arms is an advantageous feature, inasmuch as it permits the operator to turn the wheel at a speed high enough to insure practically perfect control of the movement of the blowpipe without the jerk or uneven motion that would be apt to occur if the blowpipe were moved directly or at the same rate as the operator's hand.

30 The machine being clamped on the bar which is to be cut, and the blowpipe being adjusted in the supporting arms to bring the nozzle to the proper position with respect to the bar, the blowpipe is lighted and the hand-wheel is turned. This swings the supporting arms on their centers and carries the blowpipe across the work, maintaining the blowpipe in constant parallelism with itself with the nozzle always at the same distance 35 from the surface of the bar. The cutting proceeds rapidly, the operator simply turning the hand-wheel. When the cut is finished the blowpipe need not be brought back to its original position, since the next cut

can be made by reversing the rotation of the hand-wheel.

It is to be understood that the invention is not limited to the apparatus herein specifically illustrated and described but can be embodied in other forms without departure from its spirit.

I claim:—

1. In a bar-cutting apparatus, in combination, a support adapted to be seated on a bar, a blowpipe carrier, and supporting means for the carrier, pivoted to a stationary part of the support and compelling the carrier to move independently of the bar in an arc-shaped path concentric therewith.

2. In a bar cutting apparatus, in combination, a support adapted to be seated on a bar, a pair of pivots mounted in a stationary part of the support and aligned with the axis of the bar, a pair of parallel arms fixed to the pivots at one end thereof, a pair of parallel arms fixed to the pivots at the other end thereof, a link connecting the second pair of arms to maintain the parallelism of both pairs of arms, a blowpipe carrier pivotally supported by the first pair of arms at points equidistant from said pivots, and means for rocking one of said pivots to swing both pairs of arms and move the carrier in an arc-shaped path across the bar independently thereof.

3. In a bar-cutting apparatus, in combination, a support adapted to be seated on a bar, a pair of parallel arms pivoted one above the other and above the bar on a stationary part of the support, a blowpipe carrier by and connecting the arms, a worm gear connected to one of the arms to swing the same, a worm meshing with the gear, and means for rotating the worm.

In testimony whereof I hereunto affix my signature.

CHALMERS K. BRYCE.
